LEE HERMAN SMITH, OF DETROIT, MICHIGAN.

ENGINE-STARTING DEVICE.

1,242,485.

Specification of Letters Patent.

Patented Oct. 9, 1917.

Application filed January 26, 1917. Serial No. 144,642.

To all whom it may concern:

Be it known that I, LEE HERMAN SMITH, a citizen of the United States, residing at Detroit, in the county of Wayne and State of Michigan, have invented certain new and useful Improvements in Engine-Starting Devices, of which the following is a specification.

This invention relates to starting apparatus for internal combustion engines and the like, and comprises generally a device operated by an electric motor of the type commonly used for such purposes, which motor receives its energy from any suitable source such as a secondary or storage battery.

One of the objects is to procure a starting device for the above mentioned purpose wherein the electric motor when energized is capable of automatically engaging and driving, by means of suitable intermediary members, some element connected to and operated by the engine to be started.

Another object is to secure such a starting device in which certain instrumentalities that serve to automatically engage the motor to the engine are later brought into play to automatically effect a disengagement thereof when said engine has been cranked and starts on its own power.

In connection with this automatic engaging feature my invention has as another object the provision of a mechanism wherein the working elements are very few in number, being designed and arranged to coöperate with each other in a comparatively simple and effective manner, whereby the whole device is rendered of compact construction and of reliable operation.

These and other such objects as are contemplated by the present invention will more readily become apparent to others skilled in the art after having investigated the following description, taken together with the accompanying drawing which constitutes a part of this specification, and in which drawing numerals of reference are employed for the purpose of designating the numerous parts and elements of the construction shown therein.

In said drawing the figure is a longitudinal elevation, partly in section, illustrating one embodiment of my improved starting device. This figure shows an electric motor, driving members operated thereby and adapted to coöperate with some suitable engine member, and also one manner in which

said device may be mounted in operative relation with said engine member.

Considering particularly the figure, 1 is

the frame housing of the electric motor which is provided at one end with an end plate 2. This end plate is attached to the frame 1 by means of suitable bolts 3 and is provided with a flange 4. This flange is

adapted to fit against a finished seat 5 provided in the end of the bell-housing 6 and is securely fastened thereto by bolts 7. In this manner said motor is mounted upon and supported by the bell-housing 6 in such a

way that a tight joint is provided to prevent the escape of oil or other lubricants which are commonly used within the flywheel housing of gas engines. At the other end of motor frame 1 there is shown a supporting member 8 formed integral therewith. However, if desirable, said supporting member 8

may constitute a portion of an end plate which may be secured to the frame 1 as in the case of end plate 2. It will be noted at this point that, inasmuch as the particular type and construction of the electric motor does not constitute an essential part of my invention, the showing of said motor is more or less conventional, and certain parts have

been left out entirely where it is deemed that a clearer and better conception of the invention may be accomplished thereby. At either end of the motor are bushings 9 and 10 which serve as bearings for the armature

11. Said armature is mounted for rotation upon a hollow shaft 12 one end of which rests in the bushing 10, and the other end in the bushing 9. Loosely arranged within the hollow shaft 12 is a second shaft 13 adapted

to move longitudinally back and forth therewithin and projecting at a suitable distance beyond either end thereof. This shaft 13 is journaled for relatively sliding and rotary movement in the hollow shaft 12. Fitted between the bushings 9 and 10 and their respective ends of the armature 11 are two washer elements 14 and 15, of suitable material such as felt, whose function it is to prevent the oil used for lubricating purposes from seeping beyond bushings 9 and 10 and

coming in contact with the windings of armature 11. One of said projecting ends of inner shaft 13 extends to a suitable distance within the bell-housing 6 and has fastened thereupon a driving pinion 16. Pinion 16

is secured upon said shaft as shown by means of a tapered fit therewith and a nut 17 screw

threaded upon the end of said shaft to draw said pinion firmly into place. Other methods may be used, it being essential however that the attachment be a secure one owing to the constant tendency of the pinion to work loose. This driving pinion is provided with spur teeth which are adapted to mesh with similar teeth cut or otherwise arranged about the periphery of the flywheel 18. Disposed about the said projecting end of shaft 13, and preferably at a point adjacent to the end plate 2 is a resilient element 19. This resilient element, whose function will be hereinafter described, consists of a coiled spring which may be held in its proper position upon shaft 13 by any suitable method. In the drawing I have shown the bushing 9 to project at a slight distance beyond the end of the plate 2 and, if desirable, said spring 19 may have its diameter such that when forced onto said projecting end of bushing 9 it is thereby held securely in place by means of its own resiliency. At the other end of the motor the shaft 13 has its projecting end thereof supplied with a spiral thread 20. Coöperating with the thread 20 is a member 21, which in the absence of a better term I shall hereinafter refer to as a nut. Said nut has its interior diameter provided with a spiral thread corresponding to that of shaft 13 and is also counterbored as seen for a suitable distance to permit of its being fitted onto the end of the hollow shaft 12, for which purpose said hollow shaft projects slightly beyond the end of its bearing bushing 10. A key 22 operating between the nut and hollow shaft fixes these members for corresponding rotation with each other and to further secure the nut 21 upon said hollow shaft there is provided a screw 23 having a point 24, which when set in place enters a corresponding aperture in the surface of said hollow shaft. I may extend the hollow shaft 12 and provide the same with internal threads instead of using the extending nut 21, but for facility in manufacture and assembly the use of such nut is preferable. When the several elements of the starting mechanism are in operative position as shown in Fig. 1 the shaft 13 extends to a suitable distance beyond the outer end of the threaded nut 21, and upon its extension there is an element 25. Said element is provided with an internal screw thread by means of which it may be screwed upon the end of said shaft, and to secure it against the liability of becoming loose a pin 26 passes through a hole in said element and said shaft 13, being riveted or otherwise suitably fastened therein. The element 25, when shaft 13 and pinion 16 are thus in their normal position, has the maximum portion of its mass disposed below the center of said shaft and thereby acts as a counterbalancing means tending to retard and prevent said shaft from rotating. It will be evident, of course, that the proportions and geometrical shape of this counterbalancing member are subject to various changes and modifications.

The operation of my starter may be described as follows: With the pinion 16 in its idle position and the motor at rest let it be assumed that a suitable source of power, as a storage battery (not shown) be applied to the armature 11 of the motor. As the armature 11 and the shaft 12 upon which it is mounted begin to rotate the nut 21, which is securely attached, as hereinbefore explained, upon the end of said shaft, rotates in unison therewith. Coincident with this movement the shaft 13, by reason of its own inertia and also the inertia of counterbalancing member 25, resists being rotated and is thereby moved bodily in an axial direction due to its screw threaded engagement with the nut 21. Such longitudinal movement effects the meshing of the pinion 16 with the flywheel 18. When in full meshed position therewith the said pinion has engaged and compressed the buffer spring 19 to such an extent that further relative rotation between the shaft 13 and shaft 12 is prohibited, whereby the armature 11 now applies its full driving force to the pinion 16 for the purpose of cranking the engine flywheel 18. When said engine runs on its own power and the flywheel 18 drives the pinion 16 at a speed greater than that at which it was formerly driven by the armature 11 the longitudinal thrust of the shaft 13 is reversed thereby carrying the pinion 16 out of mesh with the engine member 18. When the pinion is disengaged from said engine member the counterbalance 25 contacts with nut 21 and thereby serves to limit the outward movement of said pinion.

I have thus shown and described one method in which my invention may be put into practical use. However, I am well aware that the present embodiment is subject to numerous changes and alterations and I do not therefore wish to be limited to the exact details of construction and arrangement shown. It is believed that the scope of the appended claims is sufficient to embrace any such changes and alterations.

Having thus described and ascertained the nature of my invention what I desire to secure by Letters Patent is:—

1. A starting device having in combination with an engine driven member, an electric motor having a hollow armature shaft, a second shaft mounted within said hollow shaft and longitudinally movable with respect thereto, a driving pinion fastened upon one end of said second shaft and a spiral thread cut upon the other end thereof, a

member secured to one end of said hollow shaft having an internal thread adapted to engage the thread on said second shaft, and a counterbalancing member fastened to the threaded end of said second shaft serving to restrain the same from rotation, whereby when said hollow shaft is operated the screw threaded engagement between said internally threaded member and the second shaft acts to automatically carry said driving pinion into engagement with the engine driven member.

2. A starting device having in combination with an engine driven member, an electric motor with its armature mounted upon a hollow shaft, a second shaft within the hollow shaft and axially movable with respect thereto, a driving pinion secured upon the end of said second shaft and a spiral thread upon the other end thereof, screw threaded means upon one end of said hollow shaft actuated thereby and adapted to co-operate with the spiral thread upon said second shaft, and a counterbalancing member fastened to the second shaft serving to restrain the same from rotation, whereby when said hollow shaft is operated by said armature said screw threaded means automatically advances said second shaft to carry the driving pinion into engagement with the engine driven member substantially as described.

3. A starting device having in combination with an engine driven member, a motor having its armature mounted upon a hollow shaft, bearings in which said armature is rotatably supported; a second shaft within said hollow shaft actuated thereby for relative axial and rotary movements therewith, a pinion on one end of said second shaft and a spiral thread upon the other end thereof, said hollow shaft having a screw threaded nut keyed upon its end to coact with said spiral thread, an inertia weight fixed on said second shaft serving to hold the same from rotating, thereby allowing said second shaft to be moved automatically to carry said pinion into engagement with the engine driven member when the hollow shaft is operated, and a resilient member to absorb the shock of such engagement.

4. In a starting device for engines, in combination, an engine operated member, a motor having a hollow armature shaft, an inner shaft within said hollow shaft projecting at both ends therefrom, a pinion fastened upon one end and a counterbalance fastened to the other end of said inner shaft, a nut fastened to said hollow shaft and operating with said inner shaft to automatically move the same in an axial direction for the purpose of engaging said pinion with the engine member, said counterbalance serving to assure said axial movement of the inner shaft, and means coacting with

said pinion to absorb the shock of said engagement.

5. In a starting device for engines, in combination, an engine flywheel, a gear adapted to engage and drive said flywheel, a motor having a hollow armature shaft and an inner shaft loosely mounted therewithin, an internally threaded member rotatable with said hollow shaft and coacting with a thread on said inner shaft to automatically move said inner shaft to engage said pinion with said flywheel, and a counterbalance on the threaded end of the inner shaft to assure said engagement.

6. In a starting device for engines, in combination, an engine member, a motor having two shafts one within the other, means on the outer shaft coacting with the inner shaft to automatically move the latter into and out of driving engagement with said engine member, and means on the inner shaft for assuring its engagement with the engine member, said last means coacting with said first means to limit the movement of said inner shaft when disengaged from the engine member, as described.

7. In a starting device the combination with an engine flywheel, of a motor having its frame fastened to the housing of said flywheel, an armature and bearings therefor, a hollow shaft upon which said armature is mounted, a second shaft within the hollow shaft adapted to be moved longitudinally into engagement with said flywheel, a threaded nut on said hollow shaft co-operating with a similar thread on said second shaft, and a counter-weight on said second shaft serving to hold it from rotation whereby when the hollow shaft is operated said second shaft is automatically moved to drivingly engage said flywheel, substantially as described.

8. A starting device having in combination, an engine member, a motor shaft adapted to drive said member and having a threaded extension fastened to the end thereof, and a second shaft having eccentric and concentric members coacting therewith so that said second shaft is moved to establish a driving relation between said motor shaft and engine member, said eccentric member coacting with said threaded extension to provide a stop for the second shaft when in its normal position.

9. A starting device having in combination, an engine member, a motor shaft having an internally threaded extension fastened thereto, and a second shaft threaded to coact with the motor shaft and having driving means adapted to be operatively connected with the engine member and having a counter-weight coacting therewith to permit the shaft threads to automatically establish a driving relation between the motor shaft and engine member, said

counter-weight coating with said internally threaded extension to provide a limit for said second shaft when in its normal position.

5. 10. A starting device having in combination, an engine member, a motor having two shafts one within the other, driving means on the inner shaft adapted to be operatively connected with the engine member, an internally threaded extension on the outer shaft cooperating with the inner shaft to automatically move the driving means on the latter into driving engagement with the engine member, and means on the inner shaft for assuring said engagement.

11. A starting device having in combination, an engine member, a motor having two shafts one within the other, driving means on the inner shaft adapted to be operatively connected with the engine member, an internally threaded nut fastened to the outer shaft coating with the inner shaft to drivingly connect said driving means to the engine member, and inertia means on said inner shaft to hold the same from rotating while said driving connection is being made, substantially as described.

12. A starting device having in combination, an engine member, a motor having two shafts one within the other, driving means on the inner shaft adapted to be operatively connected with the engine member, an internally screw threaded extension fastened to the end of the outer shaft, and an inertia member fastened to the inner shaft, said threaded extension and said inertia member simultaneously cooperating with said inner shaft to automatically establish a driving connection between said driving means and engine member, substantially as described.

13. A starting device having in combina-

tion, an engine member, a motor having two shafts one within the other, driving means on the inner shaft adapted to be operatively connected with the engine member, an internally threaded extension of the outer shaft cooperating with the inner shaft to automatically move the driving means carried by the latter into and out of driving engagement with the engine member, and means on the inner shaft to hold the same from rotating while being moved into said engagement, substantially as described.

14. A starting device having in combination, an engine member, a motor having two shafts one within the other, driving means on the inner shaft adapted to be operatively connected with the engine member, screw threads on the inner shaft, screw threads on the outer shaft adapted to cooperate with the screw threads on the inner shaft, means on the inner shaft for displacing its center of gravity from the axis of rotation whereby rotation of the outer shaft causes the screw threads thereon to act on the screw threads on the inner shaft to cause the driving means on the inner shaft to move into engagement with the engine member.

15. A starting device having in combination an engine member, a motor shaft having an internally threaded extension fastened thereto, and a second shaft within the outer shaft threaded to coat with the same and having driving means adapted to be operatively connected with the engine member, and having inertia means coating therewith to permit the shaft thread to automatically establish a driving relation between the driving means on the inner shaft and the engine member.

In witness whereof I affix my signature.

LEE HERMAN SMITH.
